ABSTRACT OF THE DISCLOSURE

Piezoelectric ceramic compositions which come within the ternary system

and the binary system

and which fall within the area A, B, C, D of accompanying FIG. 2 have a combination of high dielectric constant and high electromechanical coupling coefficient which makes them useful in transducer elements and the like. Compositions within area E, F, G, H, I show even higher dielectric constant and coupling coefficient values.

This invention relates to piezoelectric ceramic compositions and articles of manufacture fabricated therefrom. More particularly, the invention pertains to novel ferroelectric ceramics which are polycrystalline aggregates of certain constituents. These piezoelectric compositions are sintered to ceramics by per se conventional ceramic techniques and thereafter the sintered ceramics are polarized by applying a D-C (direct current) voltage between the electrodes to impart thereto electromechanical transducing properties similar to the well known piezoelectric effect. The invention also encompasses the calcined product of raw ingredients and the articles of manufacture such as electromechanical transducers fabricated from the sintered ceramic.

The ceramic bodies materialized by the present invention exist basically in the following solid solutions: the ternary system $\text{Pb}(\text{Ni}_{1/3}\text{Nb}_{2/3})\text{O}_3\text{-PbTiO}_3\text{-PbZrO}_3$ and the binary system $\text{Pb}(\text{Ni}_{1/3}\text{Nb}_{2/3})\text{O}_3\text{-PbTiO}_3$.

The use of piezoelectric materials in various transducer applications in the production, measurement and sensing of sound, shock, vibration, pressure, etc. has increased greatly in recent years. Both crystal and ceramic types of transducers have been widely used. But, because of their potentially lower cost and facility in the fabrication of ceramics with various shapes and sizes and their greater durability for high temperature and/or humidity than that of crystalline substances such as Rochelle salt, piezoelectric ceramic materials have recently become important in various transducer applications.

The piezoelectric characteristics required of ceramics vary with different applications. For example, electromechanical transducers such as phonograph pick-ups, microphones and voltage generators in ignition systems require piezoelectric ceramics characterized by a substantially high electromechanical coupling coefficient and dielectric constant.

As more promising ceramic for these requirements, lead titanate-lead zirconate has been in wide use. However, it is difficult to get a very high dielectric constant along with planar coupling coefficient in the lead titanate-lead zirconate ceramics. Moreover, the dielectric and piezoelectric properties of the lead titanate-lead zirconate ceramics change greatly with firing technique which is bound up with evaporation of PbO.

2

It is, therefore, the fundamental object of the present invention to provide novel and improved piezoelectric ceramic materials which overcome the problems outlined above. A more specific object of the invention is to provide improved polycrystalline ceramics characterized by very high dielectric constant along with high piezoelectric coupling coefficient.

Another object of the invention is the provision of novel piezoelectric ceramic compositions, certain properties of which can be adjusted to suit various applications.

A further object of the invention is the provision of improved electromechanical transducers utilizing, as the active elements, an electrostatically polarized body of the novel ceramic compositions.

These objects of the invention and the manner of their attainment will be readily apparent from a reading of the following description and from the accompanying drawing, in which:

FIG. 1 is a cross-sectional view of an electromechanical transducer embodying the present invention.

FIG. 2 is a triangular compositional diagram of materials utilized in the present invention.

Before proceeding with a detailed description of the piezoelectric materials contemplated by the invention, their application in electromechanical transducers will be described with reference to FIG. 1 of the drawings wherein reference character 7 designates, as a whole, an electromechanical transducer having, as its active element, a preferably disc shaped body 1 of piezoelectric ceramic materials according to the present invention.

Body 1 is electrostatically polarized, in a manner hereinafter set forth, and is provided with a pair of electrodes 2 and 3, applied in a suitable manner, on two opposed surfaces thereof. Wire leads 5 and 6 are attached conductively to the electrodes 2 and 3 respectively by means of solder 4. When the ceramic is subjected to shock, vibration or other mechanical stress, an electrical output generated can be taken from wire leads 5 and 6. Conversely, as with other piezoelectric transducers, application of electrical voltage to electrodes 2 and 3 will result in mechanical deformation of the ceramic body. It is to be understood that the term electromechanical transducer as used herein is taken in its broadest sense and includes piezoelectric filters, frequency control devices, and the like, and that the invention may also be used and adapted to various other applications requiring materials having dielectric, piezoelectric and/or electrostrictive properties.

According to the present invention, the ceramic body 1, FIG. 1, is formed of novel piezoelectric compositions which are polycrystalline ceramics composed of

The present invention is based on the discovery that within particular ranges of these systems the specimens exhibit a very high dielectric constant along with high planar coupling coefficient.

The present invention has various advantages in manufacturing process and in application for ceramic transducers. It has been known that the evaporation of PbO during firing is a problem in sintering of lead compounds such as lead titanate zirconate. The invented compositions, however, show a smaller amount of evaporated PbO than usual lead titanate zirconate does. The invented compositions can be fired without any particular control of PbO atmosphere. A well sintered body of one of the present compositions is obtained by firing in a ceramic crucible with a ceramic cover made of Al_2O_3 ceramic. A high sintered density is desirable for humidity resistance and high piezoelectric response when the sintered body is applied to a resonator and others.

All possible compositions coming within the ternary system $Pb(Ni_{1/3}Nb_{2/3})O_3$ - $PbTiO_3$ - $PbZrO_3$ and the binary system $Pb(Ni_{1/3}Nb_{2/3})O_3$ - $PbTiO_3$ are represented by the triangular diagram constituting FIG. 2 of the drawings. Some compositions represented by the diagram, however, do not exhibit high piezoelectricity and high dielectric constant. Many are electromechanically active only to a slight degree and show low dielectric constant. The present invention is concerned only with those compositions exhibiting very high dielectric constant and piezoelectric response of appreciable magnitude. As a matter of convenience, the planar coupling coefficient (K_p) of test discs will be taken as a measure of piezoelectric activity. Thus, within the area bounded by lines connecting points A, B, C and D, FIG. 2, all compositions polarized and tested showed a dielectric constant of approximately 3000 or higher and a planar coupling coefficient of approximately 0.15 or higher. The compositions in the area of the diagram bounded by lines connecting points E, F, G, H and I, FIG. 2, exhibit a dielectric constant of approximately 3300 or higher and a planar coupling coefficient of approximately 0.50 or higher, the molar percent of the three components of compositions ABCDEFGHI being as follows:

	$Pb(Ni_{1/3}Nb_{2/3})O_3$	$PbTiO_3$	$PbZrO_3$
A	62.5	12.5	25.0
B	34.0	39.0	27.0
C	56.0	44.0	-----
D	75.0	25.0	-----
E	57.0	29.5	13.5
F	50.0	28.0	22.0
G	37.5	37.5	25.0
H	50.0	38.0	12.0
I	57.0	33.5	9.5

Furthermore, the compositions near the morphotropic phase boundary of the ternary system, particularly

and

give ceramic products having a dielectric constant of 7100 or higher and a planar coupling coefficient of 0.55 or higher.

According to the present invention, piezoelectric and dielectric properties of the ceramics can be adjusted to suit various applications by selecting the proper composition.

The compositions described herein may be prepared in accordance with various per se well known ceramic procedures. A preferred method, however, hereinafter more fully described, consists in the use of PbO or Pb_3O_4 , NiO or Ni_2O_3 , Nb_2O_5 , TiO_2 , ZrO_2 .

The starting materials, viz, lead oxide (PbO), nickel oxide (NiO), niobia (Nb_2O_5), titania (TiO_2), zirconia (ZrO_2), all of relatively pure grade (e.g., C.P. grade) are intimately mixed in a rubber-lined ball mill with distilled water. In milling the mixture care should be exercised to avoid, or the proportions of ingredients varied to compensate for, contamination by wear of the milling ball or stones.

Following the wet milling, the mixture is dried and mixed to assure as homogeneous a mixture as possible. Thereafter, the mixture is suitably formed into a desired form at a pressure of 400 kilograms per square centimeter. The compacts are pre-reacted by calcination at a temperature of around 850° C. for 2 hours.

After calcination, the reacted material is allowed to cool and is then wet milled to a small particle size. Once again, care should be exercised to avoid, or the proportions of ingredients varied to compensate for, contamination by wear of the milling balls or stones. Depending on preference and the shapes desired, the material may be formed into a mix or slip suitable for pressing, slip casting or extruding, as the case may be, in accordance with per se conventional ceramic procedures. The

samples for which data are given hereinbelow were prepared by mixing 100 grams of the milled pre-sintered mixture with 5 cc. of distilled water. The mix was then pressured into discs of 20 mm. diameter and 2 mm. thickness at a pressure of 700 kg./cm.². The pressed discs are fired at 1230-1290° C. for 45 minutes. According to the present invention, there is no need to fire the composition in an atmosphere of PbO and no special care is required for the temperature gradient in a furnace compared with the prior art. Thus, according to the present invention, uniform and excellent piezoelectric ceramic products can be easily obtained simply by covering the samples in an alumina crucible with an alumina ceramic cover during firing.

The sintered ceramics are polished on both surfaces to the thickness of one millimeter. The polished disc surfaces can then be coated with silver paint and fired to form silver electrodes. Finally, the discs are polarized while immersed in a bath of silicone oil at 100° C. A voltage gradient of D-C 4 kv. per mm. is maintained for one hour, and the discs are field-cooled to room temperature in thirty minutes.

The piezoelectric and dielectric properties of the polarized specimens have been measured at 20° C. in a relative humidity of 50% and at a frequency of 1 kc. Examples of specific ceramic compositions according to this invention and various pertinent electromechanical and dielectric properties thereof are given in the table infra. From this table it will be readily evident that the exemplary compositions selected from the area bounded by lines connecting points A, B, C, and D of the diagram of FIG. 2 are characterized by very high dielectric constant along with relatively high planar coupling coefficient.

Especially, the compositions in the area of the diagram bounded by lines connecting points E, F, G, H and I, FIG. 2, exhibit a planar coupling coefficient of approximately 0.5 or higher along with high dielectric constant.

TABLE

Ex. No.	Mole percent of composition			24 hours after poling	
	$Pb(Ni_{1/3}Nb_{2/3})O_3$	$PbTiO_3$	$PbZrO_3$	Dielectric constant, ϵ at 1 kc./s.	Planar coupling coeff., K_p
1	37.5	25.0	37.5	1,430	0.46
2	62.5	12.5	25.0	8,420	0.18
3	34.0	39.0	27.0	3,060	0.65
4	37.5	37.5	25.0	3,460	0.62
5	50.0	28.0	22.0	3,290	0.53
6	50.0	33.0	17.0	4,220	0.55
7	57.0	29.5	13.5	7,350	0.52
8	54.0	32.5	13.5	7,100	0.58
9	50.0	35.5	14.5	5,700	0.53
10	50.0	38.0	12.0	3,760	0.50
11	57.0	31.5	11.5	7,960	0.55
12	57.0	33.5	9.5	6,580	0.51
13	87.5	12.5	-----	4,080	-----
14	75.0	25.0	-----	14,570	0.15
15	71.0	29.0	-----	14,930	0.22
16	67.0	33.0	-----	8,150	0.33
17	62.5	37.5	-----	4,260	0.40
18	56.0	44.0	-----	3,310	0.37
55	50.0	50.0	-----	1,520	0.35

From the foregoing table, the values of planar coupling coefficient and dielectric constant can be adjusted to suit various applications by selecting the composition.

According to the present invention, the piezoelectric ceramics have a combination of high dielectric constant and high electromechanical coupling coefficient. Therefore, the ceramics of the invention are suitable for use in acoustic sensing transducer elements such as phonograph pickups and microphones.

In addition to the superior properties shown above, compositions according to the present invention yield ceramics of good physical quality and which polarize well. It will be understood from the foregoing that the ternary ceramics $Pb(Ni_{1/3}Nb_{2/3})O_3$ - $PbTiO_3$ - $PbZrO_3$ and the binary ceramics $Pb(Ni_{1/3}Nb_{2/3})O_3$ - $PbTiO_3$ form excellent piezoelectric ceramic bodies.

What is claimed is:

1. A piezoelectric ceramic composition consisting essentially of a solid solution of a material selected from the

area bounded by lines connecting points A, B, C and D of the diagram of FIG. 2, wherein A, B, C and D have the following formulae:

- (A) $\text{Pb}(\text{Ni}_{1/3}\text{Nb}_{2/3})_{0.625}\text{Ti}_{0.125}\text{Zr}_{0.250}\text{O}_3$
- (B) $\text{Pb}(\text{Ni}_{1/3}\text{Nb}_{2/3})_{0.340}\text{Ti}_{0.390}\text{Zr}_{0.270}\text{O}_3$
- (C) $\text{Pb}(\text{Ni}_{1/3}\text{Nb}_{2/3})_{0.560}\text{Ti}_{0.440}\text{O}_3$
- (D) $\text{Pb}(\text{Ni}_{1/3}\text{Nb}_{2/3})_{0.750}\text{Ti}_{0.250}\text{O}_3$

2. A piezoelectric ceramic composition consisting essentially of a solid solution of a material selected from the area bounded by lines connecting points E, F, G, H and I of the diagram of FIG. 2, wherein E, F, G, H and I have the following formulae:

- (E) $\text{Pb}(\text{Ni}_{1/3}\text{Nb}_{2/3})_{0.570}\text{Ti}_{0.295}\text{Zr}_{0.135}\text{O}_3$
- (F) $\text{Pb}(\text{Ni}_{1/3}\text{Nb}_{2/3})_{0.500}\text{Ti}_{0.280}\text{Zr}_{0.220}\text{O}_3$
- (G) $\text{Pb}(\text{Ni}_{1/3}\text{Nb}_{2/3})_{0.375}\text{Ti}_{0.375}\text{Zr}_{0.250}\text{O}_3$
- (H) $\text{Pb}(\text{Ni}_{1/3}\text{Nb}_{2/3})_{0.500}\text{Ti}_{0.380}\text{Zr}_{0.120}\text{O}_3$
- (I) $\text{Pb}(\text{Ni}_{1/3}\text{Nb}_{2/3})_{0.570}\text{Ti}_{0.335}\text{Zr}_{0.095}\text{O}_3$

3. An electromechanical transducer element comprising

ing a piezoelectric ceramic composition as claimed in claim 2.

4. A piezoelectric ceramic material consisting of the solid solution having the following formula:

5. A piezoelectric ceramic material consisting of the solid solution having the formula:
